UNITED STATES PATENT OFFICE.

JAMES E. ELLIS, OF RED OAK, IOWA, ASSIGNOR OF ONE-HALF TO L. M. DOCTOR, OF SAME PLACE.

CIGAR-TUCK CUTTER.

SPECIFICATION forming part of Letters Patent No. 376,030, dated January 3, 1888.

Application filed May 26, 1887. Serial No. 239,435. (No model.)

To all whom it may concern:

Be it known that I, JAMES E. ELLIS, a citizen of the United States, resident at Red Oak, in the county of Montgomery and State of Iowa, have invented certain new and useful Improvements in Cigar-Tuck Cutters; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a representation of this invention and is an end view. Fig. 2 is a vertical section taken where the dotted line $x\ x$ is marked on Fig. 3. Fig. 3 is a perspective view. Figs. 4 and 5 are details.

The invention relates to improvements in cigar-tuck cutters; and it consists in the construction and novel combination of parts, as hereinafter set forth.

Tuck-cutters as usually constructed consist of the spring-cutter, the block, (heavy enough not to be turned by the forcible depression of the cutter,) and the adjustable gage attached to the block.

In the present invention the block is made smaller, the cutter is self-cleaning, and the spring operating the cutter acts by torsion, and is of simple construction and consequently durable.

Referring to the drawings by letter, A designates the block of the cutter, small enough to be carried in the pocket, and to be firmly secured to the wrapper-board without interfering with the cutting of the wrappers.

B designates the groove in which the cigars are laid to be cut, and b is a suitably-graduated scale marked in proper position on one side of said groove.

C is the cutter-plate, secured by screws or otherwise to the front end of the block and provided with the curved notch c in line with the groove B, beveled from within outwardly, and sufficiently higher than said groove to make a cutting-edge, c', by means of the said bend. The said cutting-edge is continued upward and outward at c' from the inner part of the notch c to the top of the cutter-plate.

D is the movable knife located on the outside of the cutter-plate C, and secured upon the square projection or boss e of the rotating block E, and provided with the cutting-edge d, beveled inwardly and standing outward from the edge and nearly parallel thereto, and d' is a vertical handle, made on the outer upper corner of the knife integrally therewith, and twisted on itself to be easily handled by the thumb and finger. The knife is fitted on the square projection e of a cylindrical block, E, the washer e' and the screw e'', which enters a tapped recess in the boss e, retaining the knife in place. The lower edge, F, of the knife is curved concentrically with the pivotal screw e'', and is provided at its front and rear ends, respectively, with the shoulders f f', by means of which and the screw f'' the motion of the knife is limited in each direction. The inner end of the block E is provided with the diametrical notch G, in which rests the bent end h of the torsion-spring rod H, running axially rearward from the block E through the guide loops or staples h', and having its rear end firmly secured to the block by a screw, h', passing through a loop in said end.

I is the gage-plate, provided with the transverse arm i, against which the head of the cigar rests, and the slotted longitudinal arm i', provided on its inner edge with guide-loops i'', surrounding the spring-rod, and with the slot i'', moving on the guide-screw i', secured to the block.

By means of the scale and the gage-plate the length of the cigars is determined, and the knife and cutter-plate having their corresponding edges beveled oppositely, and the edge of the knife swinging across the edge of the cutter-plate, the cigars are sheared through with the greatest economy of force. The spring being a straight rod, acting by torsion, the space occupied by the usual outstanding spring is saved, so that the latter cannot be in the way.

Having described my invention, I claim—

1. In a cigar-tuck cutter, the movable knife provided with the cylindrical block E, the said block having the diametrical notch, the torsion-spring H, attached to the top of the block A and having its end bent so as to engage

with the notch in the block E, and the stationary blade, all constructed and combined substantially as specified.

2. In a cigar-tuck cutter, the cylindrical block E, attached to the movable cutter and provided with the diametrical notch, the torsion-spring H, attached to the top of the block A, and having one end engaging the block E and the other end attached to the opposite top end of the block A, and the gage-plate arranged

on the spring, and the stationary knife, all constructed and combined substantially as specified.

In testimony whereof I affix my signature in presence of two witnesses.

JAMES E. ELLIS.
